US00D488170S

(12) **United States Design Patent**
Sollami

(10) Patent No.: **US D488,170 S**
(45) Date of Patent: ** Apr. 6, 2004

(54) **QUICK CHANGE BIT HOLDER WITH HARDENED INSERT**

6,244,665 B1 * 6/2001 Bise et al. 299/106
6,364,420 B1 * 4/2002 Sollami 299/106

(75) Inventor: **Phillip Sollami**, Herrin, IL (US)

* cited by examiner

(73) Assignee: **The Sollami Company**, Herrin, IL (US)

Primary Examiner—Philip S. Hyder

(**) Term: **14 Years**

(74) Attorney, Agent, or Firm—Patnaude & Videbeck

(21) Appl. No.: **29/176,875**

(57) **CLAIM**

(22) Filed: **Mar. 3, 2003**

The ornamental design for a quick change bit holder with hardened insert, as shown and described.

Related U.S. Application Data

(63) Continuation-in-part of application No. 29/131,378, filed on Oct. 23, 2000, now abandoned, and a division of application No. 29/144,652, filed on Jun. 22, 2001.

DESCRIPTION

(51) **LOC (7) Cl. 15-04**

FIG. 1 is a right side elevational view of the quick change bit holder with hardened insert, showing my new design,

(52) **U.S. Cl. D15/21; D15/140**

FIG. 2 is a back side elevational view thereof,

(58) **Field of Search D15/21, 139, 140; 299/86, 90, 104, 106, 109, 110, 102**

FIG. 3 is a left side elevational view thereof,
